UNITED STATES PATENT OFFICE

2,488,963

HEEL SOCKET

Charles H. Clark, Mill Valley, Calif., assignor, by decree of court and assignment of one-half to Julia D. Clark and one-half to Paul F. Schumacher, San Francisco, Calif.

Application May 19, 1947, Serial No. 749,008

6 Claims. (Cl. 9—1)

1

My invention relates to a heel socket of that type which is adapted for use in connection with water craft and other devices for engaging and bracing the feet of individuals when propelling or operating said craft or devices, such for instance as when paddling or rowing a canoe or what I have chosen to term a cruise board. More particularly this improvement is incorporated into the deck of a cruise board, paddle board, raft or other types of water craft and other devices.

The primary object of the invention is to provide heel sockets in the deck or surface of a water craft by which the heel portion of the foot of the user may be engaged to brace a person while assuming sitting posture. Another object is to provide a heel engaging socket which is so constructed as to engage and brace the heel portion of a foot or to engage the heel portion of foot wear without causing soreness, wear or injury. Another object is the production of a heel structure which is detachably secured to the deck or other surface of an object whereby the parts of the socket structure are replaceable when worn or injured, or whenever desired. Among still further objects are maximum simplicity and effectiveness of construction and use. Another object is to provide foot bracing means on the deck or surface of a cruise board or other water craft so as to brace the feet of an individual when paddling, rowing or propelling the craft.

In the accompanying drawings forming part of this specification, Fig. 1 is a plan of my improved heel socket structure when applied to a sectional portion of the deck of a water craft, such as a paddle board or surf board; Fig. 2 is a side elevation of the structure shown in Fig. 1; Fig. 3 is a longitudinal section at increased scale taken on the line 3—3 of Fig. 1; Fig. 4 is a side elevational view of the elastic diaphragm holder when removed from the structure shown in Fig. 3, a portion thereof being broken away and in section; Fig. 5 is a plan of the filler band which is employed for holding the elastic diaphragm in distended condition in the socket member; Fig. 6 is a bottom plan of the socket frame when removed from the deck of the water craft; Fig. 7 is a sectional view taken on the line 3—3 of Fig. 1, showing the position assumed by the parts when the heel of a foot engages the socket; Fig. 8 is a plan of the deck of a cruise board at reduced scale showing the application in use of a pair of my improved heel sockets, and Fig. 9 is a side elevational view of an alternative construction of the elastic diaphragm holder, a portion thereof being broken away and in section.

2

In the drawing, A indicates in general a portion of the deck panel of what I have chosen to term a cruise board. A pair of openings such as 10 are provided in the deck panel A of the cruise board, in suitable position to receive a pair of my improved socket members, such as B, and in suitable position (Fig. 8), to be engaged by the heel portions of the feet of the person who is seated upon and propels the water craft by paddling, 10 rowing, etc. The opening 10 is elongated and sufficiently wide to freely receive either the heel portion of a foot or the heel portion of a shoe or other foot wear. An upper comparatively thick rectangular marginal frame 11 having a socket 15 opening 12 corresponding with the opening in the deck panel is placed around the latter opening and fastened in the manner hereinafter described.

A lower reinforcing frame 13, corresponding with the marginal contour of the upper deck frame 11 is secured around and below the opening 10 in the deck panel A and is fastened by screws 14 and/or other suitable means as hereinafter described, whereby a strong wear resisting marginal rim is produced around the socket opening.

A resilient diaphragm C is provided horizontally across and seals the socket opening to prevent water entering the hull of the cruise board. This diaphragm is composed of rubber or other suitable elastic or waterproof material. An elongated marginal supporting band 15 conforms with the edge of the opening 12 and has the diaphragm C fastened to its lower surface by cementing or other suitable means. The diaphragm C is retained taut across the opening within said band. The band including the diaphragm is removably held between the frame B and the upper surface of the deck panel A as shown in Fig. 3. Previous to or while the diaphragm and its outer holding band 15 are placed, an inner filler band 16 (Fig. 5) is forced upwardly into the outer band 15, whereby the elastic diaphragm is stretched and distended so that the frame B and the outer and inner bands 15 and 16 are securely and removably clamped to the deck panel A and lower reinforcing frame 13 by the application of screws 14 or other suitable means. In this manner a watertight connection is produced by my improved heel socket in the deck panel.

50 Previous to fastening the frame B and the bands 15 and 16 to the surface of the deck panel A the reinforcing frame 13 may be fastened to the inner or lower surface of the deck panel A surrounding the socket opening 10 by nailing or
55 other suitable means.

A cushioning cover D composed of relatively soft flexible waterproof or resistant material is arranged in the heel socket. This cover is formed out of a sheet of comparatively thick sponge rubber or other suitable material and is shaped with a wide body portion 20 which is fastened by cementing, nailing and/or other suitable means to the rearward portion of the surface of the frame B. Extending forwardly from the body portion 20 of the cover is a wide and comparatively long integral tongue 21 which bends down and conforms closely with the inner margin of the opening 10, thus covering and protecting the relatively thin diaphragm C. The soft surface provided by the cover D in the heel socket, cushions the heel portion of the foot or shoe when pressed against the forward stop end portion of the frame B and prevents abrasion, wear and injury of the diaphragm.

When the heel is applied against the forward end portion of the socket frame B the cover D and the diaphragm give or bend downwardly and inwardly under the weight or force applied by the foot as shown in Fig. 7, thus conforming and permitting the heel portion to engage the forward end portion of the frame in the heel socket while the diaphragm maintains the opening through the deck panel sealed.

Any water which tends to collect in the heel socket is permitted to drain and escape through the vent passages 22, over the surface of the deck panel.

In Fig. 9 an alternative construction of the diaphragm holding band 15 is provided with two elastic diaphragms C—C' which afford additional protection to prevent water leaking through the socket opening 12 into the hull of the water craft.

Modifications are contemplated within the spirit of the invention and the scope of the following claims.

I claim:

1. Heel engaging socket means for water craft, comprising a supporting deck surface having a socket opening therein, a heel engaging frame bordering the rim of said socket opening, and a resilient diaphragm removably retained by said frame, sealing said opening and adapted normally to conform with a heel when inserted in said socket and engaged by said frame.

2. In a structure as defined by claim 1, drainage duct means extending outwardly from said diaphragm.

3. Heel engaging socket means for water craft, comprising a supporting deck surface having a socket opening therein, a heel engaging frame bordering the rim of said socket opening, a resilient diaphragm retained within said frame, and a flexible protecting cover secured to said frame

and extending over the surface of said diaphragm, said cover and diaphragm being adapted to conform with the heel of an individual when said heel is inserted forwardly in said socket and is engaged by the forward end portion of said frame.

4. Heel engaging socket means for water craft, comprising a supporting deck surface having a socket opening therein, a heel engaging frame bordering the rim of said socket opening, a resilient liquid leak proof diaphragm retained within said frame and a comparatively thick resilient cushioning cover secured to said frame, extending downwardly into said socket and spread over the surface of said diaphragm to protect the latter and cushion the heel of an individual when inserted in said socket and braced against the forward portion of said frame.

5. A foot rest for engaging a heel portion of a foot or foot wear, comprising a supporting deck surface having a heel receiving socket opening therein, a heel engaging marginal frame bordering the rim above said opening, a band surrounding said opening and interposed between said frame and deck panel, an elastic diaphragm supported by said band across and sealing said opening, and means for securing said frame and band on said deck surface, said diaphragm being adapted to conform with a heel when the latter is engaged in said socket opening.

6. A foot rest for engaging a heel portion of a foot or foot wear, comprising a supporting deck surface having a heel receiving socket opening therein, a heel engaging marginal frame bordering the rim above said opening, an outer band encompassing said opening, an elastic diaphragm supported by said band, an inner band inserted in said outer band and distending said diaphragm into taut condition across the socket opening, said outer and inner bands being retained between said marginal frame and deck surface, and means for removably securing said frame and bands on said deck surface, said diaphragm being adapted to conform with a heel when the latter is engaged in said socket opening.
